(57) **CLAIM**

The ornamental design for the pair of earplugs and earphones with storage box, as shown and described.

DESCRIPTION

FIG. 1 is a front, top and right side perspective view of a pair of earplugs and earphones with storage box, showing my new design;

FIG. 2 is a rear, left and bottom perspective view thereof;

FIG. 3 is a front, top and right side perspective view of a storage box of the pair of earplugs and earphones with storage box, shown in an open position;

FIG. 4 is another front, top and right side perspective view thereof of the pair of earplugs and earphones with storage box, shown in an open position;

FIG. 5 is a front elevation view thereof, shown in a closed position;

FIG. 6 is a rear elevation view thereof;

FIG. 7 is a left side elevation view thereof;

FIG. 8 is a right side elevation view thereof;

FIG. 9 is a top plan view thereof;

FIG. 10 is a bottom plan view thereof;

FIG. 11 is a front perspective view of a left earphone of the pair of earplugs and earphones with storage box;

FIG. 12 is a rear perspective view thereof;

FIG. 13 is a front elevation view thereof;

FIG. 14 is a rear elevation view thereof;

FIG. 15 is a left elevation view thereof;

FIG. 16 is a right elevation view thereof;

FIG. 17 is a top plan view thereof;

FIG. 18 is a bottom plan view thereof;

FIG. 19 is a front perspective view of a right earphone of the pair of earplugs and earphones with storage box;

FIG. 20 is a rear perspective view thereof;

FIG. 21 is a front elevation view thereof;

FIG. 22 is a rear elevation view thereof;

FIG. 23 is a right elevation view thereof;

FIG. 24 is a left elevation view thereof;

FIG. 25 is a top plan view thereof;

FIG. 26 is a bottom plan view thereof;

FIG. 27 is a front perspective view of an earplug of the pair of earplugs and earphones with storage box;

FIG. 28 is a rear perspective view thereof;

FIG. 29 is a front elevation view thereof;

FIG. 30 is a rear elevation view thereof;

FIG. 31 is a left elevation view thereof;

FIG. 32 is a right elevation view thereof;

FIG. 33 is a top plan view thereof; and,

FIG. 34 is a bottom plan view thereof.

The broken lines in the drawings illustrate the portions of the pair of earplugs and earphones with storage box, which form no part of the claimed design.
